1 Claim, 2 Drawing Sheets

Deep Breathing Exercise

Hold your coughing pillow firmly against your incision, then do the following:

1. Take a deep breath in through your nose, and exhale slowly through your mouth puckering your lips as if blowing out a candle.
2. Take a second deep breath in through your nose as deeply as you can, exhale slowly through your mouth, again puckering your lips as you exhale completely.
3. On your third deep breath, breathe in slowly as deeply as you can.
Deep...deep...deep

Hold that breath and cough!
